UNITED STATES PATENT OFFICE.

FRANZ X. WAGNER, OF NEW YORK, N. Y.

TYPE-WRITING MACHINE.

SPECIFICATION forming part of Letters Patent No. 414,095, dated October 29, 1889.

Application filed July 26, 1888. Serial No. 281,101. (No model.)

To all whom it may concern:

Be it known that I, FRANZ X. WAGNER, a citizen of the United States, residing at New York, in the county and State of New York, have invented new and useful Improvements in Type-Writing Machines, of which the following is a specification.

My invention relates to improvements in type-writing machines; and it consists in certain novel features of construction, as fully set forth in the following specification and claims, and illustrated in the accompanying drawings, in which—

Figure 1 represents a plan or top view of a type-writing machine constructed according to my invention, a number of the keys and their connections being omitted. Fig. 1* is a sectional view of a detail part. Fig. 2 is a vertical section in the plane x x , Fig. 1. Fig. 3 is a similar section in the plane y y , Fig. 1. Fig. 4 is a vertical section in the plane z z , Fig. 2. Fig. 5 is a section in the same plane as Fig. 4, showing the parts in a different position. Fig. 6 is a plan or top view of the ribbon-actuating mechanism. Fig. 7 is a vertical section in the plane x' x' , Fig. 1. Fig. 8 is a vertical section in the plane y' y' , Fig. 1, certain parts of the rear of said section being omitted. Fig. 9 is a vertical section in the plane z' z' , Fig. 1. Fig. 10 is a vertical section in the plane x^2 x^2 , Fig. 1. Fig. 11 is a front view of one of the type-carriers, the type-bars being omitted. Fig. 12 is a rear view of the same provided with the type-bars. Fig. 13 is a vertical section in the plane y^2 y^2 , Fig. 12.

Similar letters indicate corresponding parts.

In the drawings, the letter A designates a base-plate or bed, upon which are supported the operating parts of the machine.

B , Figs. 1, 2, and 3, is the platen, which is mounted in a suitable carriage that can be swung about a pivot-bar a at the rear of the base-plate or bed. The platen is supported from below by a roller b , Figs. 2 and 3, which travels upon a horizontal guide-bar c , secured to the base-plate or bed. Suitable devices for clamping the paper to the platen and means for rotating the platen are provided, as usual. In front of the platen B are secured a pair of parallel guides C C' , into which is fitted a type-carrier D , which can freely move in a

right line between said guides. In the example illustrated in the drawings, Figs. 3, 4, 5, 11, 12, and 13, the type-carrier consists of a 55 flat metallic frame the top and bottom of which have extensions entering grooves in the guides C C' , and the type-bars E are secured to the lower portion of the frame and can swing freely about their fixed ends in a 60 plane at right angles to the plane of the carrier, Fig. 13. The type-bars may be conveniently made thin and of resilient material—such as steel—and affixed directly to the carrier by rivets or otherwise; or they may be 65 made thick enough so as not to bend and be pivoted to the carrier, suitable springs being used to return and hold them in their normal position against a suitable cross-bar or stop on the carrier. To obtain the impression of 70 any desired type, the type-carrier is moved in its guides so as to bring the said type in the correct position in line with a hammer, to be hereinafter described, and then the type-bar is pressed forward to produce the impression. 75

In the drawings each type-bar is shown provided with two types, one arranged above the other, and consequently to bring either of the same into the printing-line the carrier must be moved in a vertical plane. 80

The keys F F' and G G' , Figs. 1, 2, and 8, all have suitable guides in the base-plate or bed A , or in the key-board A' , and are held in their normal or elevated position by suitable springs. By the depression of the key 85 F or the key F' the type-carrier is moved to bring the corresponding type-bar to its correct position, and the type-carrier D is lowered to bring the upper type into the printing-line, and, finally, the type-bar is vibrated to 90 produce the impression. If one of the keys G G' is depressed, the type-carrier is moved to bring the same type-bar into the proper position, and the carrier D is raised, so as to bring the lower type into the printing-line. 95 The keys F are arranged in series of two each, as F G and F' G' , throughout the dimensions of the key-board, the said keys being arranged approximately opposite each other, Fig. 1.

The above-described effects are produced as follows: Each of the opposite keys, as F G , is provided with a cam f g , Figs. 2 and 8, which cams face in opposite directions and engage

with a rod H when the corresponding key is depressed. The main key-rod H extends horizontally across the length of the key-board and is affixed to the ends of two vertical arms 5 h h, Figs. 1 and 2, pivoted to lugs rising from the base-plate or bed. A second or supplementary key-rod H' is similarly mounted in arms h' and extends between the set of keys F' and G'. If more sets of keys are used, 10 15 20 additional key-rod are provided. The rods H and H' are connected by a link H², Fig. 3 especially, so that when either rod is moved by the depression of a key the other rod will be moved simultaneously therewith—that is to say, the rod H will be moved whenever a key is depressed. The rod H, Figs. 3 and 8, engages with the upper end of a lever i, which is pivoted on a line with the pivots of the arms h, and the free end of said lever 25 30 35 40 45 engages a slide I, located beneath the base-plate or bed. In the end of the slide is formed an oblique slot i', which engages with a rod I', Figs. 4, 5, 8, and 10. The rod I' is mounted in a lever frame i², swinging about pivots i³, so that when the slide I is moved in the direction of arrow 1, Fig. 8, the rod is moved downward, and when the slide is moved in the opposite direction the rod is moved upward.

The guides C C' for the type-carrier D are 30 35 40 45 both connected by rigid links J J' with the lever-frame i², and consequently participate in the up and down movements of the rod I', whereby the types upon the type-bars are adjusted, as previously described. A spring 35 I², Fig. 3, acting on the rod I' through an intermediate arm rigidly secured to the said rod, aids in returning the carrier-guides to their normal or central position. The connected guides C C' can be additionally steadied and guided by a pin c⁰ and slot-connection with the standard A².

Referring to Fig. 2, each of the keys F' and G' is provided with a toe j' j", both of which engage with a bent arm k K, located beneath the key-board. This arm k K is pivoted at k' to an arm K', having a pivot at k² on a lug projecting from the bottom of the base-plate or bed. To the arm k K is attached at l a lever L, which can turn about a pivot l', secured in the key-board. The lever L carries a cam L', which engages with an arm M, pivoted at m, Fig. 6, to the base-plate or bed and at m' to a T-shaped lever M', one limb M* of which carries a pin or projection m*, which 55 60 65 engages with a socket m', Figs. 3 and 10, formed in the back of a slide N, having bearings on a standard A², rising from the bed-plate. The socket m' in the slide N engages with a pin n in the carrier D, so that the carrier, Fig. 2, participates in the movements of the slide.

A cam-lever L, a bent arm k K, and arm K' are provided for each key of the key-board. By arranging the cam-levers L at a greater or 65 less distance from the pivot m² the levers M' M* will be vibrated through a less or greater distance and the type-carrier D will be moved

through a corresponding distance. The same effect could be produced by giving a greater or less pitch to the cams L'. In the standard A² are formed bearings for a hammer O, which is engaged by a bell-crank lever O', Figs. 2 and 3, pivoted at o in said standard. The free end of said lever is engaged by a lever O², Fig. 3, pivoted at o' to the key-board and provided at its outer end with two converging cam-faces o² o', which are engaged by the shaft H, so that when the latter is vibrated in either direction by the depression of a key the lever O² is oscillated to actuate the hammer to move a type which has been brought in line with the hammer against the platen.

In the type-writing machine illustrated in the drawings I have provided a second or supplementary type-carrier D', containing additional types, which carrier can be caused to take the place of the carrier D. By this means the carriers can be each provided with a less number of types, and consequently a long movement of the carriers for adjusting the type to the proper position is not necessary.

For replacing the carrier D by the carrier D', and vice versa, the following mechanism is used, (see Figs. 2, 3, 4, 5, and 7.) A slide P, having bearings in stationary posts p' and p*, carries a rack P', which is engaged by a toothed segment P², mounted on a rock-shaft p⁰. On the opposite end of the rock-shaft is rigidly mounted a toothed segment p², which is engaged by a rack p³, having the attached head p⁴. A spring P³, in conjunction with suitable stops, holds the parts normally in the position shown in Fig. 4. If the head p⁴ is depressed, the slide is moved to occupy the position shown in Fig. 5. Opposite and in close proximity to the slide P is a slide Q, Figs. 2, 3, and 9, which has a pin q and slot q' connection with the former. (See Fig. 9.) This slide Q is also supported in sockets in the posts p' and p*, and is provided with sockets q² q', Figs. 2, 3, 4, 5, and 9, which are normally out of engagement with projections or pins d d' on the carriers; but when the slide Q is moved the guides C C' for the carriers are moved laterally toward the slide, and the projections d d' engage with the sockets, so that the carriers D D' are moved with the slide to bring the same in the position shown in Fig. 5. This lateral movement of the guides C C' toward the slide Q can be produced by the action of an arm R, which is pivoted at r to the post p and engages with the lower guide. On the slide P are two wedge-shaped cams o³ o⁴, which engage in the movement of the slide with a finger r' of the arm R, so as to force the arm to turn about its pivot r to draw the guides C C' toward the slide Q. An intermediate finger r² on the arm R passes through the slot r³ in the slide Q when the arm is vibrated, and on the subsequent movement of said slide Q locks the arm in its assumed position during the movement of said slide. The cam o³ actuates the arm

R when the slide moves in one direction and the cam o^4 when it moves in the opposite direction. The object of having the pin q and slot q' connection between the slides P and Q is to permit the slide P to be moved sufficiently to cause the arm R to be vibrated, so as to move the projections dd' on the carriers well into the sockets $q^2 q^2$ in the slide Q before said slide Q is set in motion. To lock the carrier D' when idle, Fig. 4, a small projection d^2 is formed thereon, which engages with a recess d^3 , Fig. 5, formed in the standard A². The projection d^2 is withdrawn from the recess when the guides C C' are moved laterally, as before described. A similar projection d^4 and recess d^5 are provided to lock the carrier D in its idle position, Figs. 4 and 5. The carrier D' when in its operative position is brought under the influence of the same mechanism which has been described for actuating the carrier D.

For guiding each type accurately to its printing position—that is, in line with the hammer—each cam-lever L has on its free end a cavity l^2 , Fig. 10, which engages with a pin l^3 on the slide N. The levers L are so arranged that the pin l^3 is brought directly opposite the said lever, striking against a heel l^4 on the same whenever the corresponding key is depressed, Figs. 2 and 10. The heels l^4 are guided in guides l^5 on the key-board, Figs. 1 and 2, and are cut away at the portions nearest the slide N, (see Fig. 2,) so that the pin l^3 can pass them when not depressed by the key.

For letter-spacing, Figs. 2, 3, and 6, the platen-carriage is provided with a pendent rack S, the teeth of which are engaged by a dog S', pivoted at s to the end of a slide S² and capable of turning in a horizontal plane, Figs. 3 and 6. A spring s', acting on the dog S', has a tendency to turn the same about its pivot; but normally the free end of the dog is in contact with a stationary cam s², Fig. 6, which holds it in line with the slide S². The slide S² is guided by suitable means at each end and is engaged by a rod extending across a pair of bell-crank levers S³ S³, Figs. 1, 2, and 3, the opposite arms of which are united by a rod which is engaged by the lever O², which actuates the hammer, the vibration of which lever imparts a reciprocating movement to the slide S². When the slide S² is moved in the direction of arrow 2, Figs. 2 and 6, the dog S' is released from the cam s² and turns about its pivot in the direction of arrow 3, Fig. 6. On the return of the slide the dog engages with a new tooth and is turned to its original position by contact with the cam s², whereby the carriage is advanced. To prevent any lost motion between the dog and the teeth of the rack, the body of the former is made somewhat tapering, so that it fills up completely the space between two consecutive teeth.

For feeding the ribbon (not shown) the vertical spindles t t' of the spools T T' are pro-

vided with toothed wheels t² t³, (see Fig. 6 especially,) into contact with which can be thrown the feed-pawls u u', which are mounted on levers U U', having pivots u² u³, secured in a carrier U², which can be moved in the direction of its length, so as to throw the pawls u into contact with the toothed wheel t² or the pawl u' into contact with the toothed wheel t³, so as to feed the ribbon in either direction. The carrier may also be left in an intermediate position, so that both pawls are out of action. The ends of the levers U U' are united by a common pin u⁴, which engages with a slot u⁵ in the slide S² of the carriage-feeding mechanism, so that when said slide is actuated the levers U U' are vibrated about their pivots u² u³ to actuate the pawls. In order that the spools T and T' can be vertically adjusted, so as to be able to make use of the complete width of the ribbon as it becomes worn out, I feather the same to the spindles t t', and the yokes t⁵ t⁶, embracing the spools, are engaged by arms V V', Figs. 1, 2, 90 and 3, secured to a common rock-shaft V², having bearings on the key-board. A spring-handle v, attached to the rock-shaft and provided with a nib v', engaging notches v² in the base-plate, Fig. 1*, is used to actuate the 95 rock-shaft and to secure the same in position when adjusted.

What I claim as new, and desire to secure by Letters Patent, is—

1. The combination, with a type-carrier 100 movable in a right line, of the lever system M M*, the cam-levers L L', engaging said lever system, a connection between the lever system and the type-carrier, and a key for each cam-lever, whereby the depression of a 105 key actuates the type-carrier, substantially as shown and described.

2. The combination, with a type-carrier containing two or more rows of type, of a main key-rod connected with the carrier, as described, and a secondary key-rod connected with the main rod, and keys engaging with said rods, whereby the movement of the secondary key-rod is conveyed to the main rod, 110 substantially as described.

3. The combination, with a carrier containing two or more rows of type, of guides C C', for guiding the carrier in a rectilinear path, the arms J J', and the lever-frame i², supporting said guides, a rod H, carried by pivoted 120 arms h, keys F G, &c., provided with cam-faces f and g, respectively, the lever i, and slide I, provided with inclined slot engaging a rod on the lever-frame i², substantially as shown and described.

4. The combination, with a carrier provided with movable types and guided to move in a right line, of a hammer guided in bearings at right angles to the carrier, the key-rod H, a lever O', engaging said hammer, and a lever O², having cam-surfaces o² o³, engaging with the key-rod and with the lever O', substantially as shown and described.

5. The combination, with the type-carriers

D D' and the guides C C' for the same, of the slides P and Q, the shifter R, engaging the guide C' and engaged by the slide P, sockets q² q² on the slide Q, engaging the carrier, and 5 means for imparting a reciprocating movement to one of the slides, substantially as shown and described.

6. The combination, with the ribbon-spools and the toothed wheels connected therewith, 10 of the pawl-bearing levers U U', mounted on an adjustable carrier and united by a common pin u⁴, and a reciprocating slide S², engaging with said pin, substantially as shown and described.

15 7. In a type-writing machine, the combination of two rising and falling parallel guides

C C', a type-carrier fitted to said guides to move in a right line thereupon and having a series of type-bars, each containing two types, and two sets of keys F and G, and connections, substantially as described, for respectively moving the type-carrier back and forth in a right line on the guides and lowering and raising the same to bring the upper and lower rows of type into the printing-line. 20

In testimony whereof I have hereunto set my hand and seal in the presence of two subscribing witnesses.
